UNITED STATES PATENT OFFICE.

RUDOLF DIETEL, OF DUSSELDORF, GERMANY.

PLANING OR SLOTTING MACHINE FOR CUTTING SPUR GEAR-WHEELS.

1,181,648.

Specification of Letters Patent.

Patented May 2, 1916.

Application filed April 10, 1913, Serial No. 760,105. Renewed October 9, 1915. Serial No. 55,113.

To all whom it may concern:

Be it known that I, RUDOLF DIETEL, a citizen of the German Empire, residing at Dusseldorf, Germany, have invented certain new and useful Improvements in Planing or Slotting Machines for Cutting Spur Gear-Wheels, of which the following is a specification.

The invention relates to planing or slotting machines for cutting spur gear wheels with involute teeth, and more particularly to machines in which a rolling motion along its pitch circle is imparted to the blank and a reciprocatory motion to the cutter, whose forward cutting edge is directed tangentially to the root circle of the teeth to be cut. The blank is fed in the direction of said tangent and simultaneously rotated about its axis, whereby a complete tooth space is cut into the blank in a continuous operation and before the blank is divided.

In the known machines of this kind, a screw for effecting the cross-feed of the worktable is connected with a worm and worm wheel for effecting the rotation of the worktable by means of gearing, whose combined velocity ratio is equal to ratio of the pitch circle diameter of the wheel to be cut to the pitch circle diameter of the worm wheel multiplied by the ratio of the pitch of said worm wheel to the pitch of the cross-feed screw. The gearing consists of a set of change gears for driving the cross-feed screw and whose velocity ratio is equal to the ratio of the pitch of the worm wheel to the pitch of the wheel to be cut, and a set of change gears for driving the worm and worm wheel and whose velocity ratio is equal to the ratio of the number of teeth of the wheel to be cut to the number of teeth of the worm wheel. The sets of change gears are connected with each other by means of fixed gearing of a velocity ratio equal to the ratio of the pitch of the worm wheel, that is to say, the pitch of the worm, to the pitch of the feed screw.

It is the object of the present invention to dispense with the aforesaid fixed gearing, in that the change gear train for driving the cross-feed screw or the change gear train for rotating the worktable are made to equalize or compensate at the same time the difference in pitch of the worm wheel and the cross-feed screw. This is accomplished in such a manner, furthermore, that in one or the other of these change gears the ratio of

the pitch of the worm wheel to that of the wheel to be cut, or the ratio of the number of teeth of the wheel to be cut to that of the worm wheel is multiplied by the ratio of the pitch of the worm wheel to the pitch of the cross-feed screw.

In the accompanying drawings—Figure 1 is a side elevation of a machine for cutting spur gear teeth with a reciprocatory cutting tool. Fig. 2 is a partial horizontal section through the machine with the wheel blank removed. Figs. 3, 4 and 5 are diagrammatic views illustrating the manner of cutting a tooth space, Fig. 3 showing the cutting tool in its initial position relatively to the wheel blank; Fig. 4, similarly, the tool in its final position after having completed the cutting of a complete tooth space; and Fig. 5, various intermediate positions which the cutting tool successively assumes relatively to the wheel blank. Figs. 6 to 8 are fragmentary sections illustrating transmission mechanism and extended, for purposes of explanation, in one plane (not projected).

Similar characters of reference designate corresponding parts throughout the several views.

Referring to the drawings—*a* designates the worktable which is carried by the bed of a slotting machine of any desired construction and which worktable is arranged to be fed along the bed by suitable gearing *j* in well-known manner, said feed, however, having no relation to the subject matter of the present invention. The table *a* is, furthermore, arranged to have a cross-feed and a rotation about its vertical axis, both motions being obtained from a main driving shaft *b* at one side of the machine. The shaft *b* is rotated intermittently at each stroke of the tool ram at the end of each stroke of the cutting tool *c* by means of a pawl *d*, ratchet *d'* and bevel gears *d''*. Rotation of the shaft *b* is transmitted through bevel gears *e* to a shaft *f*, and thence through a gear *h* and gears *o* of variable speed ratio to a cross-feed screw *g*. Wheel *h* carries one-half of a clutch *i* whose other half is fixed to a sleeve *k* which is rotatable on and longitudinally movable along the shaft *f*. Upon the sleeve *k* is fixedly secured a gear wheel *l* which, through a set of change gears *p*, is connected with a worm shaft *m*. The clutch *i* is so constructed that only in a particular position of the two-halves thereof can the faces of the same be brought into engage-

ment, the engagement being made automatic, for example, by means of spring n , as shown. The clutch is disengaged manually.

- 5 The velocity ratios of the gearing between shaft f and feed-screw g and between the shaft f (sleeve k) and the worm shaft m may be readily varied by accordingly changing the respective change gears o or p , as is well understood. The feed-screw g effects the cross-feed of the table a by means of a nut x secured thereto and engaging said feed-screw. The worm q engages a worm wheel r fixed to the worktable and to which it, therefore, communicates its rotary motion.

- To effect the cutting of the teeth, the cross-feed and the rotation of the blank s must be so related that the motion of the 20 said wheel blank is equivalent to the rolling motion of a toothed wheel, having a pitch circle of equal diameter, along a rack. In order to obtain this motion, the velocity ratios of the gearing for the cross-feed and 25 rotation of the worktable are so chosen that the ratio of the number of turns of screw g to the number of turns of the shaft f is suited to the ratio of the pitch of the wheel to be cut to the pitch of the dividing or 30 worm wheel multiplied by the ratio of the pitch of the said worm wheel r to the pitch of the said cross-feed screw g ; while the ratio of the number of turns of the shaft f to the number of turns of the shaft m is suited to the ratio of the number of teeth of the wheel to be cut to those of the dividing or worm wheel. The speed of the cross-feed of the worktable is, therefore, as in the well-known machines, with respect to the 40 peripheral velocity of the dividing or worm wheel i as the pitch diameter of the wheel to be cut is to the pitch diameter of the said dividing wheel. It follows, therefore, that the velocity of cross-feed of the blank is 45 equal to the peripheral velocity at the pitch circle, that is to say, the motion of the blank is equivalent to the rolling motion of a toothed wheel, having a pitch circle of equal diameter, along a rack.
- 50 To cut a gear wheel, the blank s is secured in well-known manner to the worktable a and before beginning the cutting is placed in a position with respect to the cutting tool c as set forth in Fig. 3, that is to say, with the forward cutting edge of the tool 55 tangential to the root circle of the teeth to be cut. During the reciprocatory motion of the tool c , the blank is, by means of the hereinbefore described gearing, translated along said tangent toward the cutting tool and at the same time rotated about its vertical axis away from the tool, various positions of the tool relatively to the blank 60 being shown in Fig. 5. At the end of the cutting operation, after a complete tooth

space has been cut as shown in Fig. 4, the motion is reversed and blank is returned to its initial position by means of a suitable crank which may be attached to the shaft m or screw g . The clutch i is then disengaged 70 and the shaft m turned independently of the spindle g through a complete turn, whereupon the sleeve k of clutch i is automatically reengaged through the action of the spring n . Since the ratio of the number 75 of turns of sleeve k to the worm shaft m is suited to the ratio of the number of teeth of the dividing wheel, the blank is turned after a complete turn of sleeve k through an angle corresponding to the pitch of the 80 wheel to be cut. The cutting tool is then in position to begin to cut the next tooth.

Should it be desired to cut wheels having teeth of different pitch or number, it is necessary only to alter the change gears o 85 of the drive between the shaft f and spindle g or the change gears p between shaft f and the worm shaft m . Should it be desired to change both pitch and number of teeth, the change gears in both drives must 90 be altered.

In the embodiment illustrated in Figs. 1, 2 and 6 the ratio of the pitch of the cross-feed screw to that of the worm is compensated or equalized in the change gears o of 95 the drive for the cross-feed screw g . If this compensation is to be effected in the change gears p , as is set forth in Fig. 7, the dividing can no longer be effected through the medium of the clutch i , but a different dividing means must be provided and which shall operate upon the worm shaft m , for example, an indexing disk or dividing wheel. As disclosed in Fig. 7, the drive for the 100 worm shaft is provided with an index disk y which is fixedly secured to a wheel y' of the said drive and mounted upon the worm shaft m , said wheel y' and its attached index disk y being loose upon the said shaft and rotatable thereon. The coupling of the index y and wheel y' to the worm shaft m is effected by means of a pin z carried by an arm z' fixedly secured to said shaft and adapted to engage suitable perforations of the index disk, as is well understood. During the cutting of a tooth space, the index disk y and the wheel y' are coupled to the shaft m as aforesaid. When it is desired to divide, preferably after the blank has been 110 returned to its initial position with respect to the cutting tool as hereinbefore set forth, pin z is withdrawn from the index disk y . The shaft m may then be turned, independently of its gearing, by means of arm z' through the proper angle, which angle is obtained by reference to the index disk. The coupling of the shaft to its change 120 gearing is again effected through the pin z . In consequence of the fact that the clutch i is no longer necessary with the aforesaid 125 130

construction, wheel h of the shaft f may be directly connected to the change gears p for effecting the rotation of the blank.

In employing the index disk y or a dividing wheel, the combined velocity ratio of the gearing between the cross-feed screw g and the worm shaft m , which must always be equal to the ratio of the pitch circle diameter of the wheel to be cut to the pitch circle diameter of the dividing wheel multiplied by the ratio of the pitch of worm g to the pitch of cross-feed screw g , may be obtained in any suitable manner in the gearing between the said cross-feed screw and the said worm shaft. It is to be noted particularly that the velocity ratio of the shaft f to the worm shaft m need not be proportioned to the ratio of the number of teeth of the wheel to be cut to those of the dividing wheel.

In Fig. 8 is shown still another example of the manner of effecting the transmission. The arrangement therein set forth provides for the drive for the cross-feed screw g from an independent shaft t and the drive for the worm shaft m from an independent shaft u , both shafts, however, deriving their motion from the main driving shaft b . The two shafts t and u are connected, through bevel gears v and w respectively, with the driving shaft b and whose velocity ratios are in the same proportion to each other as the pitch of the cross-feed screw g is to the pitch of the dividing wheel. For example, should the pitch of the cross-feed screw g be one-half that of the dividing wheel r , the velocity ratio of shaft b to the shaft t will then be 1:1, and velocity ratio of the shaft b to shaft u , 2:1. The velocity ratio between the shaft t and the cross-feed screw g is proportional to the ratio of the pitch of the dividing wheel to that of the wheel to be cut; and the velocity ratio between the shaft u and the worm shaft m proportional to the number of teeth of the wheel to be cut to those of the dividing wheel. The combined velocity ratio between the cross-feed screw g and the worm shaft m is, therefore, proportional to the ratio of the pitch circle diameter of the wheel to be cut to that of the dividing wheel, whereby the blank has, with respect to the cutting tool, a rolling motion equivalent to that of a toothed wheel, having a pitch circle of equal diameter, 55 along a rack. The clutch i is provided on the shaft u , the bevel gear w being loose upon said shaft and attached to one of the halves of the clutch, while the sleeve k , carrying the other half and the wheel l separated from each other, is keyed to the shaft u . The dividing is effected in manner similar to that set forth in connection with the machine shown in Figs. 1 and 2.

The fixed gearing for equalizing or compensating for the difference between the

pitch of the worm wheel, that is to say, the pitch of the worm to turn the worktable, and the pitch of the cross-feed screw may thus be done away with; and the drive for the cross-feed, as well as the drive for effecting the rotation of the worktable, may each be actuated from an independent shaft, the ratio of the pitch of the worm to the pitch of the cross-feed screw being equalized or compensated by suitable choice of the velocity ratios of the bevel gears connecting the two said actuating shafts with the main driving shaft. Moreover, if the pitch of the dividing wheel be equal to the pitch of the cross-feed screw, the fixed gearing between the sets of change gears of course becomes unnecessary and the drive for the cross-feed may be directly connected with the drive for effecting rotation of the worktable.

I claim:—

1. In a machine of the character set forth: a worktable and a feed screw to impart a cross-feed motion thereto, a worm wheel and worm shaft to rotate the worktable, and intermediate connecting gearing whose combined velocity ratio is equal to the ratio of the pitch circle diameter of the wheel to be cut to the pitch circle diameter of the worm wheel multiplied by the ratio of the pitch of the worm wheel to the pitch of the cross-feed screw; change gearing for effecting the cross-feed and having a velocity ratio equal to the pitch of the worm wheel to the pitch of the wheel to be cut; change gearing for effecting the rotation of the worktable and having a velocity ratio equal to the number of teeth of the wheel to be cut to the number of teeth of the worm wheel; and equalizing or compensating gearing included in one of said sets of change gearing and having a velocity ratio equal to the pitch of the cross-feed screw to the pitch of the worm.

2. In a machine of the character set forth: a worktable and a feed screw to impart a cross-feed motion thereto, a worm wheel and worm shaft to rotate the worktable, and intermediate connecting gearing whose combined velocity ratio is equal to the ratio of the pitch circle diameter of the wheel to be cut to the pitch circle diameter of the worm wheel multiplied by the ratio of the pitch of the worm wheel to the pitch of the cross-feed screw; a main driving shaft; change gearing for effecting the cross-feed and having a velocity ratio equal to the pitch of the worm wheel to the pitch of the wheel to be cut; a driving shaft therefor; change gearing for effecting the rotation of the worktable and having a velocity ratio equal to the number of teeth of the wheel to be cut to the number of teeth of the worm wheel; a driving shaft therefor; and equalizing or compensating gearings connecting said main driving shaft respectively with the said

riving shaft for the cross-feed and with the said driving shaft for effecting the rotation, the velocity ratios of the said respective compensating or equalizing gearings bearing to each other the same relation as the pitch of the cross-feed screw to the pitch of the worm wheel.

3. In a machine of the character set forth: a worktable and a feed screw to impart a cross-feed motion thereto, a worm wheel and worm shaft to rotate the worktable, and intermediate connecting gearing whose combined velocity ratio is equal to the ratio of the pitch circle diameter of the wheel to be cut to the pitch circle diameter of the worm wheel multiplied by the ratio of the pitch of the worm wheel to the pitch of the cross-feed screw; a main driving shaft; change gearing for effecting the cross-feed and having a velocity ratio equal to the pitch of the worm wheel to the pitch of the wheel to be cut; a driving shaft therefor; change gearing for effecting the rotation of the work-

table and having a velocity ratio equal to the number of teeth of the wheel to be cut 25 to the number of teeth of the worm wheel; a driving shaft therefor; equalizing or compensating gearings connecting said main driving shaft respectively with the said driving shaft for the cross-feed and with 30 the said driving shaft for effecting the rotation, the velocity ratios of the said respective compensating or equalizing gearings bearing to each other the same relation as the pitch of the cross-feed screw to the pitch 35 of the worm wheel; and disengaging means included in the compensating or equalizing gearing for the drive shaft of the rotation producing change gearing.

In testimony whereof, I have signed my 40 name to this specification in the presence of two subscribing witnesses.
